[57] **CLAIM**

The ornamental design for the identifying tag for bottled beverages, as shown and described.

DESCRIPTION

FIG. 1 is a front elevational view of an identification tag for bottled beverages showing my new design, with the broken line showing for illustrative purposes only and forming no part of the claimed design;

FIG. 2 is a rear elevational view thereof, with the broken lines of the bottle showing for illustrative purposes only and forming no part of the claimed design;

FIG. 3 is a left side elevational view thereof;

FIG. 4 is a right side elevational view thereof;

FIG. 5 is a top plan view thereof; and,

FIG. 6 is a bottom plan view thereof.

FIG. 1

FIG. 2

FIG. 3

FIG. 4

FIG. 5

FIG. 6
